UNITED STATES PATENT OFFICE.

LA FAYETTE BENNETT, OF SALT LAKE CITY, UTAH.

LIGHT-GLOBE PROTECTOR.

Application filed December 7, 1925. Serial No. 73,620.

My invention relates to electric light globes, and has for its object to provide a new and economical protector for the globes which will prevent breaking them when roughly handled, and which may be drawn over and protect any sized globe from twenty-five to one hundred and fifty watts, and may be made in sizes to fit smaller or larger globes.

10 A further object is to provide an attractive protector which will not obstruct the rays of light to any appreciable extent.

Fig. 1 is a detail view of the protector comprising my invention.

15 Fig. 2 shows my device as applied to an electric bulb.

Fig. 3 is a front end view of the device shown in Fig. 1.

These objects I accomplish with the device illustrated in the accompanying drawings in which similar letters of reference indicate like parts throughout the several views, and as described in the specification forming a part of this application and 25 pointed out in the appended claims.

The device consists of a plurality of spiral coils A, with the ends of each wire fastened together, to form an annular coil band. The several annular coils A are held in spaced 30 apart relation to each other by longitudinally disposed spiral springs B having much smaller convolutions than those of the coils A and with the convolutions of the springs B passed through the convolutions of the 35 springs A where they pass each other. In order that the circumferential enlargement of one of the annular coils A will be limited I provide a wire C which is passed through

the annular coil A and its ends fastened forming a wire ring and holding that end of the device from enlargement, and in using the device the globe is slipped through the opposite end and longitudinally into the device until the globe reaches the annular coil A which carries the wire C. The resiliency 45 of the device will allow its being used over any style or type of globe.

Having thus described my invention I desire to secure by Letters Patent and claim:—

1. A light globe protector consisting of 50 pieces of fine spring wire formed as coil springs with the ends of the wire fastened together giving each coil spring an annular band form; other pieces of fine spring wire formed as spiral springs, with some of the convolutions of the spiral springs engaging some of the convolutions of the coil springs to space them apart; and a wire band within the annular coil spring at one end of the 55 protector.

2. A light globe protector consisting of a cylindrical resilient member made of a plurality of spaced apart fine spring wires, made in the shape of coil springs, with the ends of each coil secured together to form an 60 individual annular coil; other coil springs placed at right angles to the first springs and having the convolutions of the last-mentioned coil springs engaging with some of the convolutions of the first-mentioned coil springs 65 to hold them in longitudinal resilient relation to each other.

In testimony whereof I have affixed my signature.

LA FAYETTE BENNETT.
